PRINTING ATTACHMENT FOR BOTTLE
LABELING MACHINES

Norman G. Creamer, Huntington, W. Va., assignor to Edward Ermold Company, Hudson, N. Y., a corporation of New York

Original application January 18, 1938, Serial No. 185,496. Divided and this application April 28, 1938, Serial No. 204,742.

2 Claims. (Cl. 101—335)

This invention relates to printing attachments for bottle labeling machines for the purpose of printing the labels of the known labeling machine with the date and initials of the factory. Such printing may be either upon the body or neck labels, or both, or upon the revenue stamps. The present application is a division of application Serial No. 185,496 filed January 18, 1938.

Heretofore, difficulties have been encountered in the printing of such labels, particularly from the fact that the imprinting applied soon faded out, so that the printing became more or less illegible.

The object of the invention is to provide a printing attachment in which the ink flows continuously from the ink reservoir to the printing pad so as to assure at all times an ample supply of ink to the pad, and thereby give a distinct and visible imprint upon the label by the type inked by the pad.

The object of the invention is, further, the provision of an attachment to standard labeling machines so arranged as to operate therewith, preferably in series of four, six or eight for the body or neck labels, or both, as desired, to enable about two hundred labels per minute to be printed, substantially simultaneously with the labeling of the bottles by the labeling machine. In other words, the invention comprises the co-operation of the known labeling machine with the printing attachment, so that when the bottles are out of the way the printing of the label or labels for the next bottle or bottles may take place, and when the printing device is out of the way, the next bottle may be labeled.

Furthermore, the use of a pad placed in a vertical position while inking the type, assures a good supply of ink to the type prior to its inking. The invention includes means to carry out the foregoing objects.

The invention will be more fully described hereinafter in the light of the embodiments thereof shown in the drawings, and will be finally pointed out in the claims.

The invention consists of further features which will also be described in the light of the embodiments shown in the drawings, and will also be finally pointed out in the claims.

In the accompanying drawings:

Figure 1 is a front elevation of the known parts of a labeling machine, showing one body label mechanism and one neck label mechanism applied thereto;

Figure 2 is a section taken on the line 2—2 of

Figure 1, showing a body label printing mechanism in printing position;

Figure 3 is a section like Figure 2, but in "off" position;

Figure 4 is a section taken on the line 4—4 of Figure 1, showing a neck label printing mechanism, in printing position;

Figure 5 is an enlarged sectional view taken on the line 5—5 of Figure 1 of the lower part of the body label printing mechanism shown in Figure 2;

Figure 6 is a sectional view of the parts of Figure 5, but in "off" position;

Figure 7 is a front elevation taken on the line 7—7 of Figure 5, seen in the direction of the arrows; and

Figure 8 is an exploded view of the inking device and pad.

Similar characters of reference indicate corresponding parts throughout the various views.

Referring to the drawings, and more particularly to Figure 1, parts of a standard labeling machine are shown, which in and for themselves form no part of this invention.

As is known, the bottles B of any shape pass over table 10 in the direction of the arrow A in Figure 3, and are brought into a position so as to receive body and neck labels, when moved into the space 14, in proximity to the piles L and N, in a manner well known.

The side frames 12 of the machine have slots or spaces 14 to accommodate label feed mechanism, and rest on the base 11 in Figure 3. Horizontally disposed stiffening rods 15 and 16 connect the outer frames 12, shaft 15 being used as a pivot rod, and rod 16 is used also in actuating the providing device.

As shown, rotating shaft 17 in the base 11 carries an oval-shaped cam 18. A fork-shaped member 19, having a semi-circular cam 20 and cam roller 21, is actuated by the movement of the cam 18 into and up and down movement. The following known elements are set in operation thereby: Rod 22, (see Figures 2 and 3), lever 23 on stationary pivot 24, link 25, lever 26, movable bar 27, and S-shaped bar 28 which is at 30 linked to arm 29 keyed on shaft 15. Lever 26 is rigidly secured to the bar 27, so that as link 25 ascends, bar 27 is moved upwardly and hence bar 28 is also moved upwardly, as seen in Figure 2.

The interposing unit thus described between rod 22 and shaft 15 is oscillated and moves the bar 27 and other known parts of the labeling machine, not necessary to describe or show as no claim is made thereto.

The bar 27 of the standard labeling machine, which bar extends between the side frames 12 of the machine, supports the units or attachments for printing the labels, indicated generally by 5 35 and 46 in Figure 1. The bar 27 carries a bracket member 40, the lower part of which connects with a lever 43 on a pivot pin 42. This bracket member 40 has a pin 44a to which a spring 44 is secured, and the other end of the 10 spring 44 is secured to a pin 44b on the lever 43. The spring 44 pulls on the lever 43, and thus presses its curved part 43a against the cross rod 16. The yoke 40 also supports a supporting member 72, which extends downwardly below the 15 pivot pin 42, and in turn supports at its lowermost end a member 71 holding the type-chase 78 and type 79, as shown in Figure 5. The type 79 is locked in its chase 78 by screws 79. The bar 72 is also adjustable by a nut controlled bolt 20 73 (Figures 2 and 4) which moves the bar 72 against the action of a spring 80. Spring 80 acts on bar 72, and spring 44 acts on lever 43.

The chase 78 is locked in position on the member 71. The member 71 with the chase 78 and 25 type 79 is vertically adjustable on the bar 72 by bolts 80 movable in a guide slot in the bar 72. The member 71 has a pivot pin 51. An ink pad support 50 is pivotally movable on this pin 51. This pad 54 is swung up against the type 79 by 30 the lever 43 which is connected with the member 50 by a pivot pin 59, the pin 59 engaging a slot 43b of the lever 43 and being eccentrically positioned to the pivot pin 51. If then, the lever 43 at its curved portion 43a presses against the rod 35 16, it moves against the opposing action of the spring 44, and turns on its pivot 42, whereby its lower free end presses upon the pin 59, and thereby moves the upper part of member 50 in a direction around the pivot 51, and hence moves the pad 40 54 of the support 50 against the type 79. A stop 77 is provided against which the pad supporting member 50 abuts when the pad is in its non-inking position. The felt pad 54 has a bore 55 into 45 which a tube 56 is inserted. These parts are shown in separated positions in Figure 8, but in Figure 7 they are shown in assembled position. The ink reservoir 60 has a filler cap 61, and a draw cock 62. The ink flows, being regulated by control valves 63, through the piping 64 and flexible 50 rubber hose 65, down into the small tube 56, and out of the holes 57 thereof into the felt pad 54, to saturate the same with ink.

It will have been seen that the attachment to a standard labeling machine comprises a member 55 40 which supports the swinging lever 43, on the pivot 42, and which lever 43 moves the pad into and out of inking position against the type, the pad being fed by the ink reservoir. It will be particularly noted that the pad when in noninking 60 position is in a horizontal position, and when in inking position is in a vertical position, thus allowing the ink to move therein against the pad felt, when inking, and thereby giving a greater amount of fluid to the type than when type is moved 65 against a horizontal pad.

The attachment for carrying out the inking operation moves with the parts of the labeling machine, and in relation thereto, the bar 27 moving from the position shown in Figure 3 to that in 70 Figure 2, and vice versa, the inking reservoir moving with said bar 27. Thus, the printing of the top label on the pile can take place and then the printing mechanism passes out of the path of the

space 14, whereupon the bottle B can enter the space 14, and be labeled with the printed label, in the manner well known.

It will also be seen that when the parts are in the position shown in Figure 3 and Figure 6, the inking takes place, i. e., when the type is against the pad. Thus, the non-printing position is the inking position. When, however, the frame 27 is moved, and a period in the labeling operation permits, then printing can take place immediately 10 from the inking position. With the frame 27 near to rod 16, as in Figure 3, the curved lever 43 pressing against rod 16 has its lower end substantially below its upper end, with the printing and inking mechanism out of the way, and the pad 15 against the type, as also shown in Figure 6. But, when bar 27 moves inwardly over the space 14, to carry out its labeling function, the lever 43, in pressing against the bar 16, enables its other end to move against the label pile and do the printing 20 as shown in Figure 2 and in Figure 5.

It will have been seen that the invention described hereinabove includes a unit consisting of a printing mechanism attachment to a labeling machine, which consists in the embodiment shown 25 of a supporting member 40 secured to the movable bar 27 of a labeling machine. To this member 40 is pivoted a lever 43 having a curved portion 43a pressing against the cross rod 16 of a labeling machine, which lever is spring actuated by the 30 spring pressing the lever 43 against the rod 16. The lever 43 extends below the pivot 42 and supports a printing mechanism consisting of a chase 78 and type 79, and a swingable inking pad normally in vertical position covering the face of the 35 type, and swingable in a non-inking horizontal position, together with means for supplying the pad with ink. By the combination of such a unit with a standard labeling machine, the printing mechanism is put in operation to print labels 40 before they are supplied to the bottles, when the labeling of the bottles is inactive, and vice versa.

It is obvious that various changes and modifications may be made in the details of construction and design of the above specifically described 45 embodiments of this invention without departing from the spirit thereof, such changes and modifications being restricted only by the scope of the following claims.

I claim:

1. In an attachment for printing labels, an ink pad having a bore, a holder for the ink pad, a tubular insert for the bore of said pad and having openings, a stationary ink reservoir, flexible 55 means guiding the ink from said stationary reservoir to said insert, and a pivoted lever supporting said ink pad holder for moving said ink pad holder, the tubular insert and bore in the pad permitting relative movement of the ink pad in respect to the insert in the bore during the movement of the ink pad by the pivoted lever.

2. In an attachment for printing labels, an ink pad having a bore, a holder for the ink pad, a tubular insert for the bore of said pad and having openings, a stationary ink reservoir, flexible 65 means guiding the ink from said reservoir to said insert, and movable means supporting said ink pad, and holder in horizontal position, the insert in the bore of the pad permitting relative movement of the pad in respect to the insert, when the pad is moved from horizontal to vertical position 70 by the movable means.

NORMAN G. CREAMER.
